UNITED STATES PATENT OFFICE.

PETER KELLER, OF CHICAGO, ILLINOIS.

CARBURETOR.

SPECIFICATION forming part of Letters Patent No. 431,059, dated July 1, 1890.

Application filed November 7, 1889. Serial No. 329,472. (No model.)

To all whom it may concern:

Be it known that I, PETER KELLER, a citizen of the United States, residing at Chicago, in the county of Cook and State of Illinois, have invented new and useful Improvements in Carburetors, of which the following is a specification.

My invention relates to certain improvements in carburetors of that class which I have described in the United States Patent No. 353,811, granted to me November 30, 1886.

The peculiar and novel construction of my carburetor is pointed out in the following specification and claim, and illustrated in the accompanying drawings, in which—

Figure 1 represents a vertical central section. Fig. 2 is a horizontal section in the plane $x x$, Fig. 1.

In the drawings, the letter a represents the storage-chamber for the hydrocarbon liquid, and the lower compartment b , I term the "evaporating-chamber." The top of the storage-chamber is provided with a vent and filling-tube c c' , each of which is provided with a stop-cock d d' , and also with a screw-cap e e' , respectively, for closing the ends of said tubes. The storage and evaporating chambers are separated from each other by a horizontal partition or diaphragm f , in the center of which is an opening g , through which passes a valve or guide-rod h , carrying a valve i fixed thereto and of suitable form to correspond with the seat made around said opening. The valve-rod extends up through a yoke and is subjected to the action of a spring l' , which is so adjusted that it retains the valve in its seat against the downward pressure, which is exerted by the liquid in the storage-chamber upon the upper face of the valve i . The upper end of the valve-rod is guided in a tubular projection formed on or secured to the top of the storage-chamber. This projection is closed by a screw-cap. The vessel forming the storage and evaporating chambers is hermetically sealed and placed within and entirely covered by another vessel r , provided with a hollow projection s , situated on the top thereof, and inclosing both the vent and the filling-tubes of the storage-chamber. This hollow projection s is provided with a cover s' , adapted to be locked or otherwise fastened thereto. There is in the

base of the hollow projection an opening t , through which water is supplied until it shall have reached above the vent and filling-tubes. 55 Arranged diametrically opposite to each other are two vertical pipes v' v^2 passing from the main gas-pipe v and extending therefrom to the evaporating-chamber. One of these vertical pipes extends at a suitable distance below the 60 partition f , while the other stops flush with the under surface of this partition.

From the under surface of the partition f extends a pipe l nearly to the bottom of the evaporating-chamber b . This pipe is open at 65 its bottom end, and it surrounds the valve i , so that said valve can open downwardly. In the interior of the evaporating-chamber may be suspended strips b' of felt or other absorbent material. 70

Mode of operation: The storage-chamber a is supplied with a suitable hydrocarbon liquid through one of the pipes c or c' , and by depressing the valve i a portion of this liquid is permitted to flow down into the evaporating- 75 chamber, and it rises therein to the level indicated in Fig. 1 of the drawings. When this has been accomplished, the pipes c c' and the projection s are closed and the pipes v' v^2 are opened. As the gas escapes from the pipe v' 80 it spreads over the surface of the hydrocarbon liquid in the evaporating-chamber b , so that it absorbs the vapors rising from this liquid, and it then escapes through the pipe v^2 . As the vapors rising from the hydrocarbon liquid 85 are carried off, the level of this liquid in the evaporating-chamber sinks down and a partial vacuum is formed in the upper portion of the pipe l , so that the valve i opens automatically and a fresh supply of hydrocarbon liquid 90 runs down into the evaporating-chamber. As the hydrocarbon liquid rises in the pipe l , the air in the upper part is compressed and the valve g closes again, and in this manner the operation progresses until the liquid in the 95 storage-chamber is used up.

I do not claim in this application for a patent anything shown and described in my Patent No. 353,811; but it will be seen that by extending the pipe l below the level of the 100 liquid in the evaporating-chamber and near to the bottom thereof the float-valve m described in said patent can be dispensed with, and the valve i is caused to open and close

simply by the alternating rarefaction and compression of the air in the upper portion of the pipe *l*.

What I claim as new, and desire to secure 5 by Letters Patent, is—

The combination, with the storage-chamber *a*, the gas supply and discharge pipes *v' v²*, the evaporating-chamber *b*, and the valve *i*, of the pipe *l*, open below and extending close

to the bottom of the evaporating-chamber, to substantially as described.

In testimony whereof I have hereunto set my hand in the presence of two subscribing witnesses.

PETER KELLER.
